US0D1069797S

(12) **United States Design Patent** (10) Patent No.: **US D1,069,797 S**
(45) Date of Patent: ** Apr. 8, 2025

(54) **SCANNER**

(71) Applicant: **PFU Limited**, Kahoku (JP)
(72) Inventors: **Koichi Nakamura**, Kahoku (JP);
Satoshi Kuroda, Kahoku (JP); **Hiroshi Shiraiwa**, Kahoku (JP); **Shinya Orita**, Kahoku (JP)

(73) Assignee: **PFU Limited**, Ishikawa (JP)

(**) Term: **15 Years**

(21) Appl. No.: **29/893,390**

(22) Filed: **May 30, 2023**

(30) **Foreign Application Priority Data**

Feb. 10, 2023 (JP) ..... 2023-002459 D

(57) **CLAIM**

The ornamental design for a scanner as shown and described.

DESCRIPTION

FIG. 1 is a perspective view of a scanner showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines in the drawings show portions of the scanner that form no part of the claimed design.

1 Claim, 7 Drawing Sheets
